UNITED STATES PATENT OFFICE

WILLIAM L. MAPPES, OF CINCINNATI, OHIO, ASSIGNOR TO THE THOS. J. CORCORAN LAMP CO., OF CINCINNATI, OHIO, A CORPORATION OF OHIO

CLOSURE FASTENER AND REFLECTOR SEAL FOR LAMPS

Application filed July 13, 1927. Serial No. 205,510.

The type of lamps to which this invention applies particularly is the usual automobile lamp. In such lamps there are found such elements as a body within which a reflector is located and which is closed by a glass held in place by a closure rim on the body, with an electric lamp bulb located within the reflector.

An object of this invention is to accomplish by an improved device a securing of the rim to the body with less effort than heretofore, with greater security than heretofore, and without rotation of the closure rim relatively to the body.

A further object is to produce such a closure fastener and reflector seal as will more effectively cause a sealing of the reflector against the entrance of dirt and moisture thereto, with an independently operated means for causing the closure to be fastened and other independent means for sealing the reflector.

These and other objects are attained in the closure fastener and reflector seal which I am about to describe and which is shown in the accompanying drawings, in which;

Fig. 1 is a complete sectional elevation of an automobile lamp embodying my invention.

Fig. 2 is a fragmental sectional elevation of an automobile lamp embodying my invention, but showing a slight modification of the form shown in Fig. 1.

Fig. 3 is a fragmental sectional elevation of a form of my invention suggested by those shown in Figs. 1 and 2, but embodying a modification relating to the reflector sealing mechanism.

Fig. 4 is a fragmental sectional elevation of a modification of the reflector sealing device.

Fig. 5 is also a modification of the devices shown in the foregoing figures.

Figs. 6 and 7 are further modified forms of my invention.

The form of invention shown in Fig. 1 is embodied in the usual form of automobile headlamp which has a body 8, a closure rim 9, and a reflector 10, with a lamp bulb 11 located within the reflector, and a closure glass 12 over the reflector. This glass 12 is provided

with a packing ring 13 between it and the edge of the reflector 10. The bulb 11 is mounted in the reflector within a connector 14 which is of fixed focus type in that no adjustment is provided to move the bulb in or out to adjusted positions as to focal position of its filament with relation to the reflector.

The rim 9 is provided with a rear edge which is inturned to form an annular hook 15. The forward edge of the body is annularly shouldered and is inturned to form an engaging edge for fingers 16 which extend from the branches 17 of a forked member 18. This forked member 18 is the closure retainer and operates as such by reason of the hooked ends 19 which engage the annular hooked edge 15 of the closure. The central portion 20 of the forked member 18 is threaded to receive an adjustment screw 21 and thereby to act as a nut thereon. A head 22 on the screw 21 serves to bring about adjustment thereof. This causes forward or backward movement of the retainer 18 and consequently of the hooked ends 19 thereof for tightening or releasing action upon the lamp closure.

At this point I will show how the fingers 16 operate. As will be seen, they are inclined and bear against the inner edge of the inturned edge of the body. The reason for this bearing of the fingers against the forward edge of the body is that the branches 17 of retainer normally tend to spring apart and consequently in addition to this the hooked ends 19 are held within the annular rim 15. Now when the retainer 18 is moved forwardly, the fingers slide over the inturned annular edge of the body and as the hooks 19 move forwardly away from the annular hook 15 the fingers in sliding over the body edge 23 will simultaneously draw the hooks 19 within the body beyond chance of engagement with the closure rim. Thus the rim may be removed. A reverse operation of course takes place when the retainer is drawn back by the adjusting screw thus again locking the rim in position.

An additional feature of my invention consists in providing a fork 24 which is screw threaded to receive a screw 25 which is rotatable within the adjustment screw 21 and

accessible from the rear by means of a screw driver in the screw head slot. A pair of cotter pins 26 and 27 are provided in the screw, the former to prevent displacement of the fork 24 therefrom and the latter to hold the screw 25 from displacement from screw 21. The forward ends of the fork engage the rim of the reflector from its rear side and are located within the annular groove at the back 5 of the reflector opening. By adjusting screw 25 the fork is moved forwardly thus pressing the reflector against the packing ring 13 to seal it against dust and moisture.

In Fig. 2 a slight modification of Fig. 1 is 15 shown. This merely consists in forming fork 18 so that the ends of the fork tend to spring toward each other, with the fingers engaging the reflector edge to move the hook ends of the fork outward when the fork is 20 drawn backwardly by the screw 25. On forward movement of the fork the hook ends release from the annular edge of the closure 25 rim and the fingers permit them to spring toward each other and to withdraw within the lamp body, thus releasing the closure rim.

Fig. 3 shows a slight modification of the idea disclosed in Fig. 1, in that instead of the fork 24 I have provided a thimble or cupped shaped projection 28 at the rear of the reflector, in which the screw 25 operates. 30 Thus the reflector may be as readily forced forwardly or drawn backwardly as though it were controlled by the fork 24 as shown in Fig. 1.

Fig. 4 is intended to show the idea that the fork, whether it applies to the reflector or closure rim control may be equipped with 35 more than two branches if desired. In this disclosure the fork is double in that it is provided with four branches instead of two as 40 in the preceding disclosures.

Fig. 5 is a disclosure of a form of the invention resembling Fig. 2, but instead of the fingers 16 of the fork engaging the reflector as in Fig. 2 for spreading the branches thereof into hooking engagement with the door rim, these fingers engage the rim 29 beyond a notch 30 which has been cut therein. In this form the branches 17 are allowed to spring inwardly as the fork is moved forwardly, thus 45 releasing the closure rim as in Fig. 2.

Fig. 6 shows the idea which incorporates the principle of the devices I have described, but instead of the fork branches 17' being arranged to spring outwardly or inwardly and under control of a finger on each, I have arranged for the fork branches to slide straight forwardly and to have a hook on each extending outwardly and engaging the annularly hooked edge 15' of the closure rim. 50 Thus in the movement of the hooked ends of the fork branches forwardly the closure rim is loosened but not released. The releasing is then accomplished by providing 55 a hole 31 in the closure rim opposite the posi-

tion occupied by the hooked end of the forked branch so that the insertion of a mere nail or similar article through this hole will engage the hook of the fork branch and push it within the body free of the annular hooked edge of the closure rim so that the rim can be withdrawn freely.

And finally, I have shown a form of the invention in Fig. 7, in which a flat hook 32 is soldered or otherwise attached to the closure rim with a flat hook shaped end 33 of the fork member in engagement therewith, a sloping wall 34 of the fork branch bearing against and sliding over the edge of the in-turned body rim. In this construction the normal spring of the fork branches is outwardly, hence the hook 33 which engages the hook 32 when the fork is drawn backwardly, will be moved out of contact with the hook 32 when the fork is moved forwardly, thus releasing the closure for removal from the body.

Having thus described my invention what I claim is:

1. A combined closure fastener and reflector seal for lamps comprising a detachable closure rim capable of axial movement for attachment and detachment purposes, a glass closure in the rim, a lamp body to receive the rim, a reflector within the body and capable of axial movement therein, means for drawing the rim to secured position relatively to the body, a second means for moving the reflector away from the body toward the rim and into sealing engagement with the glass closure, and concentrically arranged adjustment screws for functioning said first and second means independently.

2. In a lamp closure and reflector sealing device the combination of a lamp closure rim, a body to receive said rim, a screw within the body, a forked element attached to the rim detachably and to the body centrally between its ends by means of the screw, a reflector in the body, a second screw within the first mentioned screw, a second forked element engaging the reflector to obtain movement thereof relatively to the body, by engagement of the ends of the forked element with the reflector through adjustment thereof by the second mentioned screw.

In testimony whereof I have hereunto affixed my signature.

WILLIAM L. MAPPES.
